UNITED STATES PATENT OFFICE.

CHARLES E. LUCKE, OF NEW YORK, N. Y., ASSIGNOR TO GAS AND OIL COMBUSTION COMPANY, OF NEW YORK, N. Y., A CORPORATION OF DELAWARE.

METHOD OF BURNING EXPLOSIVE GASEOUS MIXTURES.

1,146,725.

Specification of Letters Patent.

Patented July 13, 1915.

Application filed September 21, 1912. Serial No. 721,558.

To all whom it may concern:

Be it known that I, CHARLES E. LUCKE, a citizen of the United States, residing at New York city, in the county of New York and State of New York, have invented certain new and useful Improvements in Methods of Burning Explosive Gaseous Mixtures, fully described and represented in the following specification and the accompanying drawings, forming a part of the same.

This invention relates to a method of burning explosive mixtures continuously, or non-explosively as distinguished from non-continuous or intermittent combustion of such mixtures. In an application filed by me on the 21st day of September, 1912, Ser. No. 721,557, I have described a method of burning explosive gaseous mixtures by causing the mixture to flow in one or a number 20 of jets or streams from nozzles with a velocity greater than the rate of propagation of inflammation through the mixture, and while flowing unconfined to impinge upon the surface of a freely porous and permeable bed of suitable material, whereby it is caused to spread out laterally with loss of 25 velocity and to enter or tend to enter the pores or passages of the bed, and then burning the mixture where the velocity of flow equals the rate of propagation of inflammation and permitting the products of combustion to escape through the passages or 30 pores of the bed. As pointed out in said application, the combustion may be caused 35 to locate at the surface of the bed or within the bed, the location of the combustion surface or zone depending upon the character of the bed and the velocity, size and character of the impinging jet or jets, and also 40 to some extent upon the character of the explosive mixture. In said application I have claimed this method broadly and I have also claimed specifically in said application the method of burning the mixture beyond the 45 impact or baffling surface, or within the bed.

The present invention relates to the burning of explosive mixtures at or against a baffling or impact surface. In burning explosive mixtures in accordance with the 50 method claimed herein, the mixture is caused to flow unconfined with a velocity greater than the rate of propagation of inflammation and its flow velocity is then reduced to the rate of propagation of inflammation by causing it to impinge against

and spread over the surface of a porous and permeable bed and it is then burned at the impact surface, the products of combustion being allowed to escape through the passages or pores of the bed. Under the influence of the burning mixture the impact surface of the bed becomes highly incandescent 60 and radiates both heat and light to a high degree. With the free escape of the gases of combustion through the bed beyond the impact face, and if the surface of the bed is of a proper character, the outwardly facing surface of each part or particle of the face of the bed will be actually or practically in contact with a part of the explosive mixture at the time when its velocity has been 65 reduced to the rate of propagation of inflammation so that combustion will take place against such surface. Interposition of unburned or burning gases between the surface of the bed and the burned gas is thus avoided and the temperature of the impact surface of the face of the bed is raised to the highest value physically possible so that it becomes, as above stated, highly incandescent, radiating both heat and light to a 70 high degree.

The impact bed of an apparatus for use in practising the method of this application may be of any suitable character or construction to provide the necessary pores or passages for the escape of the products of combustion and may be of any suitable material. For a lasting or permanent bed, a suitable refractory material, that is, one 75 which will withstand the degree of heat to which it is subjected, must be used. I have found chrome ore, alundum, magnesite, lime and carbon to be suitable materials, and with comparatively weak mixtures fire brick 80 will answer. It is not necessary that the bed be of any considerable thickness and it may be formed by a comparatively thin perforate or porous diaphragm or plate. The passages through the bed need only be of such 85 character as to provide for the free escape of the products of combustion, and need not, therefore, be intercommunicating or expanding as in an apparatus for burning the mixture within the bed. The degree of 90 porosity and permeability should, however, be such as to permit such free escape of the products of combustion that with a given rate of feed of mixture the mixture will burn 95 substantially in contact with all of the phys- 100 105 110

ical surface over which the advancing stream spreads.

To secure the highest temperature and incandescence of the surface of the bed, the surface of the bed should be of such a character or have its surface particles or parts so shaped as to promote proportionate passage of the mixture between the parts or particles and to prevent to the greatest degree the retention of a dead layer of gas on the side toward which the mixture is advancing. A bed of broken or other suitable granular refractory material with the pieces either loose or bonded meets all the requirements. Such a bed may be in the form of a thin plate or diaphragm or may be of any desired thickness. It is desirable also that the impact face of the bed be shaped according to the character and shape of the jet or jets of mixture caused to impinge thereon so as to secure the desired spread of the mixture with reduction of its flow velocity to the rate of propagation of inflammation. Also the bed may be of various shapes according to the purpose to which the invention is to be applied, and a single bed or a number of beds suitably grouped and arranged may be employed, the character and arrangement of the impinging jets corresponding to the arrangement and shape of the bed or beds.

It should be noted that the heating of the advancing mixture as it approaches the surface of combustion tends to increase the rate of propagation of inflammation, thus promoting the attainment of equality between the rate of propagation and flow velocity and thereby increasing the amount of mixture that can be burned at a given surface and within a given space. A similar acceleration of the rate of combustion is believed to be contributed by the incandescent solid matter.

It will be understood that by the term "explosive gaseous mixture" as used herein is meant a mixture of a suitable combustion supporting gas, either oxygen alone or air or other oxygen-containing gas, with combustible matter in a gaseous or other finely divided state in proper proportions, that is, in proportions such that the mixture will have the property of self-propagation of inflammation. For producing the highest temperature, the oxygen should be undiluted and the mixture should contain oxygen and combustible matter in chemical combining proportions at the time of combustion; but there may be an excess of either the combustible matter or the combustion supporting gas within the limits which determine the property of self-propagation. The character of the mixture in this respect will depend upon the desired character of the products of combustion, that is, whether it is desired that the products shall be neutral,

oxidizing or reducing. Also, the mixture may of course contain neutral gas such as nitrogen, carbon dioxide or water vapor, so long as the amount of such neutral gas is not sufficient to make the mixture non-explosive. 70

The accompanying drawings illustrate simple forms of apparatus adapted for carrying out my improved method.

In said drawings; Figure 1 shows a simple form of single jet apparatus, partly in section. Fig. 2 is a similar view showing a modified form of apparatus; Fig. 3 is a sectional view of another modified form of apparatus by which a plurality of jets of the explosive mixture are discharged against 80 the impact face of the bed; Fig. 4 is a similar view of a still further modified form of apparatus; and Fig. 5 is a similar view of a form of apparatus in which the fuel and combustion supporting gas are supplied 85 from separate nozzles.

Referring to Fig. 1, 10 represents a porous and permeable combustion supporting bed against which a jet or stream of the explosive mixture is directed by a discharge pipe or nozzle 11. The mixture may be supplied to the nozzle from any suitable source or by any suitable means and should be supplied under sufficient pressure to cause the jet or stream issuing from the nozzle to move toward the bed with a velocity greater than the rate of propagation of inflammation through the mixture. This figure shows a mixture-supplying means or apparatus for supplying a mixture of fuel gas and combustion supporting gas and which comprises a tank G for the fuel gas and a tank A for the oxygen or air or other combustion supporting gas, the two gases being supplied to the respective tanks by suitable means adapted to maintain the necessary pressure therein. An outlet leads from each tank controlled by valves *a* and *g* respectively and from these outlets a supply pipe 12 leads to the discharge pipe or nozzle 11. The valves *a* and *g* serve to control the proportions of fuel gas and combustion supporting gas in the mixture and the velocity of flow of the mixture from the nozzle 11 may also be controlled by these valves. 110

The proper proportions of fuel gas and combustion supporting gas, that is, proportions such according to the nature of the constituent gases that the mixture will have the property of self-propagation of 120 inflammation, may be readily determined by experiment. When the jet or stream of mixture issuing from the nozzle 11 strikes the face of the bed 10 it will spread out over the face of the bed and its flow velocity will be reduced. By properly adjusting the supply of mixture by means of the valves *a* and *g*, the jet may be given such an exit velocity in excess of the rate of propagation of inflammation of the mixture 130

that when the jet is baffled and caused to spread at the face of the bed 10 its velocity will be thereby reduced to the rate of propagation of inflammation so that when the 5 mixture is ignited the flame cap or surface of combustion will locate against the impact surface of the bed. The products of combustion may, and the greater part of the same will, then pass away from the combustion 10 zone or surface through the pores or passages of the bed and escape from a part of the surface of the bed other than the impact face, combustion thus taking place in accordance with the method of this 15 application. As there is a very considerable reduction in the flow velocity of the mixture when it strikes and spreads out over the impact face of the bed, the combustion will remain localized at the impact face under 20 quite considerable variations in the velocity of the impinging jet so that an extremely accurate adjustment of the supply pressure of the gas and the velocity of the jet is not necessary in order to maintain the combustion 25 so localized.

In order that the combustion zone or surface may coincide more or less accurately with the impact face of the bed throughout the greatest possible or a considerable 30 extent thereof, the impact face should be shaped according to the character of the jet. With a single solid jet issuing from a cylindrical orifice, and with the mixture impinging at substantially right angles against the 35 face of the bed, the impact face should be of circular concave shape as indicated by Fig. 1. In this figure I have shown the combustion supporting bed as formed of a mass of loose broken or other granular 40 refractory material such as lime, carbon, chrome ore, alundum or magnesite in a suitable container 14. With such a bed the products of combustion will escape from the portions of the upper surface of the bed 45 rounding the impact surface as indicated by the arrows, or the container 14 might have outlet openings 15 as indicated by dotted lines. With a combustion supporting bed formed of granular material or otherwise 50 formed to cause a gas flowing therethrough to expand or spread out laterally as it advances, the combustion surface or zone may be caused to enter and become localized within the bed as explained in my said application No. 721,557 by increasing the velocity 55 of the impinging jet of explosive mixture, or by moving the nozzle toward the bed. As already pointed out, however, it is not necessary when the combustion is to be localized at the impact face of the bed, that the bed should be of such character 60 as to cause the expansion or lateral spreading of gases advancing through it.

Fig. 2 shows a combustion supporting 65 bed intended for combustion only at the im-

pact face, the pores or passages through the bed having a uniform capacity or cross area from the impact face to the rear face of the bed and being thus adapted to serve to carry away the products of combustion but not 70 to cause a gradual decrease of velocity of gas flowing through them. This figure shows, also, a nozzle 11^a having an annular discharge orifice for discharging a jet which is annular in cross section and which 75 as shown is of a slightly flaring form. The impact surface of the bed for receiving this annular jet is formed with an annular concave face for the same reason that the impact face of the bed for receiving a solid straight jet is best formed circularly 80 concave.

Fig. 3 shows a plurality of nozzles or other openings arranged to discharge jets of explosive mixture against the impact 85 face of a bed in the form of a thin plate, the pores or passages in which are provided by simple perforations.

Fig. 4 shows a burner having a combustion supporting bed 20 in the form of an 90 annular plate or diaphragm having a slightly concave flaring outer surface against which the explosive mixture is directed from an annular series of nozzle 95 openings in a circular pipe 21 to which the mixture is supplied through a pipe 22.

Fig. 5 illustrates a form of apparatus in which the fuel gas or other form of fuel and the air or other combustion supporting 100 gas are supplied separately from nozzles 30 and 31 respectively set so that the jets of fuel and combustion supporting gas will meet at or near the impact face of the bed to form an explosive mixture which, driven by the force of the air jet or the fuel jet 105 or both, spreads out with consequent loss of velocity and, the initial velocity of the jets being properly adjusted, burns at the impact surface of the bed, the products of combustion escaping as before in great part 110 through the pores or passages of the bed. This form of apparatus, that is, one by which the fuel and combustion supporting 115 gas are mixed adjacent the impact face of the bed, may be used where the fuel is in the form of a gas but is especially adapted for use when oil or other liquid fuel is supplied in the form of a jet or spray to be vaporized as it reaches or approaches the impact surface of the bed where the combustion is 120 located, the vapor then mixing with the air or other combustion supporting gas to form the explosive mixture which then spreads out over the surface of the bed as before explained to be burned.

The combustion supporting bed or diaphragm shown in Fig. 4, also the bed shown in Fig. 5, may be of any suitable freely porous and permeable material. They might be made, for example, by molding a plastic 130

mass of suitable refractory material to which has been added matter which on being heated will disappear.

It will be understood that apparatus of various other forms may be used for practising the invention and that any desired number of jets arranged in various ways and jets of various forms may be employed in connection with suitably arranged porous and permeable beds.

What is claimed is:

1. The method of burning explosive gaseous mixtures, which consists in supplying the mixture continuously and driving it unconfined with a velocity greater than the rate of propagation of inflammation through the mixture toward the surface of a porous and permeable bed, whereby the mixture is caused to spread out over the impact surface and its flow velocity reduced to the rate of propagation of inflammation, and burning the mixture at the surface of the bed and allowing the products of combustion to escape through the passages of the bed.
2. The method of burning explosive gaseous mixtures, which consists in causing the mixture to flow unconfined with a velocity greater than the rate of propagation of in-

flammation through the mixture and then reducing the velocity to the rate of propagation by causing the mixture to flow against and spread out over a part of the surface of a porous and permeable bed, and burning the mixture at the impact surface, and allowing the products of combustion to escape through the passages of the bed.

3. The method of producing heat, which consists in combining a fuel in a finely divided state with a combustion supporting gas in proportions to form an explosive mixture, driving the explosive mixture unconfined at a velocity greater than the rate of propagation of inflammation of the mixture against the surface of a porous and permeable bed of refractory material the temperature of which is sufficient to cause ignition of the mixture, and burning the mixture at the impact surface of the bed and allowing the products of combustion to escape through the passages of the bed.

In testimony whereof I have hereunto set my hand in the presence of two subscribing witnesses.

CHARLES E. LUCKE.
